UNITED STATES PATENT OFFICE.

ISAAC FRANCIS TAYLOR, OF LONDON, ENGLAND, ASSIGNEE OF ONE-HALF TO SAMUEL PICK, OF LONDON, ENGLAND.

WINCH.

1,159,290.

Specification of Letters Patent.

Patented Nov. 2, 1915.

Application filed April 7, 1915. Serial No. 19,830.

To all whom it may concern:

Be it known that I, ISAAC FRANCIS TAYLOR, a subject of the King of Great Britain and Ireland, residing at 5 Upland road, 5 East Dulwich, London, S. E., England, have invented certain new and useful Improvements in Winches, of which the following is a specification.

This invention relates to winches for use 10 in launching boats or for other purposes or generally to hoisting gear in which the winding barrel or barrels is or are adapted to be disengaged from the hand or power operated driving shaft and controlled during 15 the lowering of the load by a brake drum or drums.

The invention has for its objects to enable the lowering or raising of loads and particularly the lowering or raising and trimming 20 of boats to be effected and controlled with greater ease and facility than heretofore.

With the above objects in view the improved winch comprises a winch barrel or barrels with a brake drum or drums thereon 25 actuated through a hand or power operated countershaft geared to the barrel or barrels by spur gearing, and worm gear adapted to transmit the power to the countershaft and applied thereto in such manner that the 30 shaft can be moved longitudinally to put same out of gear with the winch barrel or barrels as hereinafter described.

When the winch is employed on board 35 ship to coöperate with the usual davits one winch barrel is provided for lowering or raising the boat and another for slewing the davit. The winches may also be used with davits of the pivoted cantaliver type, and may be worked separately or coupled for 40 ease of control.

Hand and foot levers are provided to control the gear and brake mechanism of the winch such controlling levers being arranged on the winch framing or on an over-head platform or bridge.

In the accompanying drawings Figures 1 and 2 are side and end elevation respectively of a winch constructed according to this invention part of the end framing being 50 broken away in Fig. 2. Fig. 3 is a side elevation showing two winches coupled together and adapted to be controlled from a distance, Fig. 4 is an end elevation of same, Figs. 5 and 6 illustrate the controlling levers and platform in elevation and

plan respectively, and Figs. 7 and 8 are sectional elevations at right angles illustrating on a larger scale worm and spur gearing employed in operating the winches.

As shown in Figs. 1 and 2 the winch comprises end frames *a a* connected by distance stays *b* and provided with bearings for two barrels *c d* each carrying a fixed spur gear wheel *c¹ d¹* at one end with which a pinion *e* carried on a countershaft *f* is adapted to be put in mesh by moving the shaft *f* longitudinally as hereinafter described. Barrel *c* is intended for hauling, slewing or other purposes but in some cases may be dispensed with, while barrel *d* is intended for raising 70 or lowering loads and is provided with a brake drum *g* acted upon by a brake band *g¹* operated by a hand lever *g²* to control the lowering of the load. Ratchet wheels *h h¹* are also provided on the ends of the winch 75 barrels and are engaged by pawls *i i¹* pivoted on the winch framing for holding the barrels against rotation in one direction. Worm gear illustrated in detail in Figs. 7 and 8 is employed for transmitting the power to the countershaft *f*. Part of this shaft on which a worm wheel *j* is mounted is made square in cross section or provided with a feather and adapted to slide 80 in the worm wheel so that the shaft *f* can be moved longitudinally to put its pinion *e* out of gear with the spur wheel on either 85 winch barrel or into gear as desired. By this means the worm wheel can always remain in engagement with its driving spindle or worm *k* which can be driven directly by a hand crank *l* as shown or through spur gear *m n*. The shaft *f* is supported on the winch frame by bearing collars *o* having 90 roller or ball bearings *p*, and is moved longitudinally by a hand lever *r* which is held in its extreme position by a notched bar or catch *r¹* engaging the end frame of the winch. In some cases a spring *s* is coiled 95 on the shaft *f* and tends to move the pinion *e* into gear with the gear wheel *d¹* of the drum *d*.

In the construction shown in Figs. 3 and 4 in which two winches of the general character described are coupled together, a shaft 105 *t* extends across both winch frames *a a* on which it is journaled and carries a pair of spur wheels *u u¹* which can both be put in mesh with the spur wheels *d d¹* on the winch barrels *d* to gear the said barrels to 110

gether, or the shaft t may be moved out of gear leaving the barrels free to rotate independently under the control of the cranks l or brake drums. For this purpose the shaft t carrying the spur wheels u u^1 is mounted to slide longitudinally in the winch frames and is moved by an angle lever u^2 pivoted in a bracket u^3 and actuated by a suitable lever. By this construction the winch barrels d d can be rotated simultaneously at the same rate by actuating one or both driving cranks and will wind up or pay out their ropes to a corresponding extent, or they may be disconnected to pay out or wind up the ropes at different rates, for example, to enable a boat to be trimmed when used for lowering same.

The winch barrels c are divided transversely by a central flange and each receives two ropes which are wound thereon in opposite directions, such ropes being attached to a davit or other device required to be slewed or adjusted about a vertical axis. In this case the retaining pawl i is lifted out of engagement while the barrel is rotating and held in the disengaged position by a pivoted strut or latch i^2 which is pivoted to the end of the pawl i and which can be thrown into contact with the winch frame so as to hold the pawl in the disengaged position. In this case the various controlling devices for the brake drums and gears are shown with connections broken away but intended to lead to a controlling platform with hand and foot levers as shown in Figs. 5 and 6.

The brake bands g^1 are connected by levers g^2 rods g^3 and bell crank levers g^4 with controlling hand levers g^5 pivoted at g^6 on the bridge or platform v while angle levers r^2 arranged to operate the shafts f are connected through rods r^2 , angle levers r^4 and rods r^5 with the upper end of a pivoted arm r^6 pivotally connected with a rod r^7 which is coupled by a sliding collar r^8 to the lever g^5 . A grip lever x mounted on the lever g^5 engages the collar r^8 and causes the connections r^3 to r^7 to move in unison with the lever g^5 when same is being de-

pressed to apply the brake band, so that the shaft f is actuated to free the winch barrel corresponding to the brake simultaneously with the application of the brake, but the said shaft f can be moved into gear before the brake handle is released by pressing the grip lever x to release the collar r^8 and connections r^3 to r^7 controlling the shaft f . A foot lever y is connected in a similar manner to the hand lever g^5 with the angle lever u^2 which adjusts the coupling shaft t .

What I claim and desire to secure by Letters Patent is:—

1. A winch comprising a pair of winch barrels, brake drums controlled by brake bands and levers, means for gearing the barrels together in such manner that they can be rotated simultaneously at the same rate to wind up or pay out the ropes or disconnected to enable the barrels to be rotated at different speeds, worm gear arranged to transmit power to the winch barrels and independent of said means, and means for disengaging the winch barrels from the worm gear.

2. A winch of the character set forth, comprising in combination a winch barrel, a brake drum for said barrel, a brake band for said drum, means for winding said barrel adapted to be thrown into and out of gear, an operating bridge or platform, connections leading from said platform for operating the brake band, and connections leading from said platform for controlling said winding means, and a releasable grip connecting said band connections with said winding means connections whereby the winding means may be thrown out of operation simultaneously with the application of the brake, but that the winding means can be thrown into operative position before the brake is released.

In testimony whereof I have affixed my signature, in presence of two witnesses.

ISAAC FRANCIS TAYLOR.
